(57) CLAIM

The ornamental design for a baseball tray plate, as shown and described.

DESCRIPTION

FIG. 1 is a top plan view of a baseball tray plate showing my new design;

FIG. 2 is a bottom plan view thereof;

FIG. 3 is a right side elevational view thereof;

FIG. 4 is a front view thereof;

FIG. 5 is a left side elevational view thereof;

FIG. 6 is a rear view thereof; and,

FIG. 7 is a perspective view thereof.

The baseball tray plate embodiments of the present invention provide a specially designed tray plate for sporting events, parties, and other get-togethers for fans and groups, and individuals. The device can be used as a plate and be kept as a souvenir to remind the fan or individual of the event. It should be recognized that embodiments of the design have the following unique items:

The baseball tray plate will be shaped like a baseball. There will be the hole in the middle of the plate, approximately 3 inches in diameter that will hold a drinking cup. The hole will be raised where it can also serve as a food divider. The seams of the baseball will be used as a divider for food items. The plate will be textured similar to a baseball for a realistic appearance.
